DESIGN FOR A NAME FINDER

Albert J. Meier, Kirkwood, Mo.

Application September 11, 1937, Serial No. 71,574

Term of patent 14 years

To all whom it may concern:

Be it known that I, Albert J. Meier, a citizen of the United States, residing at Kirkwood, St. Louis County, Missouri, have invented a new, original, and ornamental Design for a Name Finder, of which the following is a specification, reference being had to the accompanying drawing, forming part thereof.

Fig. 1 is a perspective view of a name finder showing my new design.

Fig. 2 is a side elevation thereof.

What I claim is:

The ornamental design for a name finder, substantially as shown.

ALBERT J. MEIER.
